UNITED STATES PATENT OFFICE

152,884

DESIGN FOR A CLOTHESLINE REEL

Francis Johnson, Detroit, Mich.

Application June 10, 1948, Serial No. 146,879

Term of patent 14 years

(Cl. D49—1)

To all whom it may concern:

Be it known that I, Francis Johnson, a citizen of the United States, residing at Detroit, in the county of Wayne and State of Michigan, have invented a new, original, and ornamental Design for a Clothesline Reel, of which the following is a specification, reference being had to the accompanying drawing, forming a part thereof.

In the drawing:

Figure 1 is a front elevation of a clothesline reel, showing my new design;

Figure 2 is a top plan view of the clothesline reel shown in Figure 1; and

Figure 3 is a side elevation of the clothesline reel shown in Figure 1.

I claim:

The ornamental design for a clothesline reel, as shown.

FRANCIS JOHNSON.
